J. W. BOND

TYPEWRITING MACHINE

Filed Oct. 25, 1919

INVENTOR:

Joseph W Bond
By
B. Stickney
ATTORNEY.

UNITED STATES PATENT OFFICE.

JOSEPH W. BOND, OF PHILADELPHIA, PENNSYLVANIA, ASSIGNOR TO UNDERWOOD TYPEWRITER COMPANY, OF NEW YORK, N. Y., A CORPORATION OF DELAWARE.

TYPEWRITING MACHINE.

Application filed October 25, 1919. Serial No. 333,351.

To all whom it may concern:

Be it known that I, JOSEPH W. BOND, a citizen of the United States, residing in Philadelphia, in the county of Philadelphia and State of Pennsylvania, have invented 5 certain new and useful Improvements in Typewriting Machines, of which the following is a specification.

This invention relates to typewriting machines. In such machines, including those of Underwood manufacture, it is customary to incorporate a tabulating key at the keyboard, to enable the carriage to be brought rapidly and correctly to any desired letter-space in its travel, the carriage 15 being arrested by the previously set stop.

In many Underwood typewriting machines, this tabulating key is usually placed adjacent the upper right-hand corner of the 20 keyboard. Other forms of the Underwood standard typewriting machine, however, have other forms of tabulating mechanism, and some of these include a stop-setting key. This key is adapted to set any one of a 25 large number of stops.

This stop-setting key is usually at the upper right-hand corner of the table in the Underwood typewriting machine, with the result that the typist, accustomed to use an 30 ordinary tabulating mechanism, will sometimes inadvertently depress the stop-setting key when typewriting on a machine having such a key, the typist thinking that the stop-setting key is the tabulating key. This 35 confusion of the typist is especially likely to occur in large offices, where both kinds of typewriting machines are used, and the typist uses one for one kind of work, and another for another kind of work.

According to the present invention, the typist may guard against this confusion by setting to effective position a guard or stop, which is adapted to interfere with the stop-setting key, and thus warn the typist if it 45 is attempted to tabulate by that key. The typist may keep the stop or guard normally effective and only release it during the stop-setting operation.

Other features and advantages will hereinafter appear.

In the accompanying drawings,

Figure 1 is a skeleton perspective rear view of a stop-setting key with a co-operating stop or guard.

Figure 2 is a fragmentary perspective

view of part of an Underwood typewriter keyboard, showing the present invention as applied thereto.

In one form of Underwood standard typewriting machines, the carriage 1 has fast 60 thereto a rack-bar 2, extending substantially the length of the carriage, and carrying stops 3 which are mounted in openings 4 at letter-space intervals over the major portion of the length of the carriage. Usually 65 there is a stop 3 in each opening 4, and the stops normally occupy the upper unset or ineffective position at which the stops are shown in Figure 1. These stops are adapted to co-operate with any one of a set of 70 decimal key-operated counter-stops 5, of any usual or desired form.

When it is desired to move any one of the stops 3 from its unset to set position, the typewriter carriage is shifted to bring the 75 unset stop beneath the stop-setting arm 6, formed as a turned-over end of a plunger 7, which is adapted to be drawn down by the depression of the stop-setting key 8.

The connections between the key 8 and the 80 plunger 7 include a key-lever 9, which is pivotally connected by a link 10 to a rock-arm 11, fast upon a rock-shaft 12, said shaft also having fast thereto a rock-arm 13, to which the plunger 7 is pivotally connected. 85 Normally, the plunger 7 is held up by the usual returning spring 14 of the key-lever 9. The stop-setting key 8, as seen in Figure 2, in some forms of mechanism, stands adjacent the decimal tabulating keys 15 and 90 the character-printing keys 16, both of said sets of keys forming part of the Underwood keyboard and lying within the ends 17 of the frame.

After all of stops 3 have been set which 95 the typist desires to set, a guard 18 may be swung from its ineffective position, seen in Figure 1, to the effective position, seen in Figure 2, to interfere with the operation of the key. The guard 18 is herein shown as 100 a stop or arm pivoted at 19 upon a bracket 20, held by screws 21 to the frame of the machine, and comprising a plate 22 adapted to swing beneath the key 8 and to be arrested by the upturned end 23 of the key-lever. It may include an annular rim 24 105 adapted to fit around the periphery of the key 8, and from the rim may project a finger-piece or lug 25, to permit the arm 18 to be swung to and from effective position. It 110

will be seen that the part to co-operate with the key forms substantially a half of a cup enclosing one-half of the key when in effective position. The screw which forms the pivot 19 may fit closely enough upon the arm 18 to detain the arm in any position to which it is shifted.

It will be seen that the arm or stop may be swung by the lug 25 clear of the key 8, when it is desired to set stops 3, and that, when the stops have been set, the blocking of the operation of the key, after the arm 18 has been swung to effective position, will be a warning to the typist whenever it is attempted to operate that key.

Variations may be resorted to within the scope of the invention, and portions of the improvements may be used without others.

20 Having thus described my invention, I claim:

1. In a typewriting machine, the combination with a traveling carriage, of stops thereon at letter-space intervals, a frame for 25 the machine, keys forming part of a keyboard and including a tabulating key and a stop-setting key, and a device permanently shiftable from a normally ineffective position to a position for preventing any actuation of the stop-setting key by mistake for 30 the tabulating key.

2. In a typewriting machine, the combination with a traveling carriage, of stops thereon at letter-space intervals, a frame for 35 the machine, keys forming part of a keyboard and including a tabulating key and a stop-setting key, a bracket on said frame, and a lug pivoted upon said bracket to be swung under the stop-setting key and substantially into engagement with the lower 40 face thereof to hold the stop-setting key against actuation.

3. In a typewriting machine, the combination with a traveling carriage, of stops 45 thereon at letter-space intervals, a frame for the machine, keys forming part of a keyboard and including a tabulating key and a stop-setting key, a lever for the stop-setting key, an arm pivoted to swing upon said 50 frame and having an extension to be swung immediately beneath the stop-setting key, when the latter is in its normal position, and be arrested by said lever, and a lug extending above said key and adjacent thereto 55 to enable the typist's finger to shift the arm to and from effective position.

4. In a typewriting machine, in combination, a plurality of settable column-stops at letter-space distances, a stop-setting key, 60 means whereby any one of said column-stops may be set by said key, and means to prevent the accidental setting of a column-stop by said key while typing, comprising a fixed bracket having a horizontal lug a short distance below the lower face of said stop-set-

ting key, an arm pivotally mounted on said lug so as to be swung in a substantially horizontal plane, said arm being provided at its outer end with a portion constituting substantially half of a cup, the bottom of which 70 passes immediately beneath the lower face of the key, and the raised portion or rim of which partially embraces the key around the periphery thereof, and a finger-piece extending upwardly from the rim of the cup so 75 as to facilitate movement of said arm to and from effective position.

5. In a typewriting machine, the combination with a stop-setting key, of a bracket adjacent said key, an interfering device 80 pivoted on the bracket to be swung beneath the key to prevent actuation thereof and having an upwardly-extending portion to engage said key to check the movement of said interfering device, and a finger-piece for 85 operating the device.

6. In a typewriting machine, the combination with a tabulating key, a stop-setting key and a key-lever on which said stop-setting key is secured, of a bracket adjacent 90 said stop-setting key, an interfering device pivoted on the bracket to be swung beneath the stop-setting key and against said key-lever to be arrested thereby, and a lug on the device extending above the stop-setting key 95 and adjacent thereto and forming a finger-piece for swinging it to and from effective position.

7. In a typewriting machine, the combination with a tabulating mechanism including a 100 tabulating key, a set of settable column-stops and a stop-setting key therefor, of a device on said machine, settable at will, for locking the stop-setting key against actuation when typing is to be effected. 105

8. In a typewriting machine having a keyboard and a carriage, the combination of a mechanism for tabulating said carriage, including a tabulating key at said keyboard, to enable the carriage to be brought rapidly 110 and correctly to any desired letter-space in its travel, said tabulating mechanism also inclusive of a large number of settable stops, a key for setting said stops individually, said stop-setting key being also located at said keyboard and therefore liable to be depressed by mistake for said tabulating key, and a guard constructed to interfere with the use of said stop-setting key, thereby to prevent its manipulation when the tabulating key is intended; said guard releasable to permit the setting of stops by said stop-setting key preparatory to a tabulating operation. 115

9. In a typewriting machine, in combination, a plurality of settable column-stops at letter-space distances, a stop-setting key, a lever for said key, means whereby any one of said column-stops may be set by said key, and means to prevent the accidental setting 120

of a column-stop by said key while typing, comprising a fixed bracket having a horizontal lug a short distance below the lower face of said stop-setting key, an arm pivotally mounted on said lug so as to be swung in a substantially horizontal plane, said arm being provided at its outer end with a portion constituting substantially half of a cup, the bottom of which passes immediately beneath the lower face of the key and is cut away to embrace the key-lever im-

mediately below said key, and the raised portion or rim of which partially embraces the key around the periphery thereof, and a finger-piece extending upwardly from the rim of the cup so as to facilitate movement of the arm to and from effective position,

JOSEPH W. BOND.
